UNITED STATES PATENT OFFICE.

JOHN S. BLAKELY, OF KANSAS CITY, MISSOURI.

GRAIN-METER.

SPECIFICATION forming part of Letters Patent No. 742,959, dated November 3, 1903.

Application filed January 19, 1903. Serial No. 139,517. (No model.)

To all whom it may concern:

Be it known that I, JOHN S. BLAKELY, a citizen of the United States, residing at Kansas City, in the county of Jackson and State of Missouri, have invented certain new and useful Improvements in Grain-Meters, of which the following is a specification.

My invention relates to improvements in grain-meters; and my object is to provide a machine of this character which will accurately and rapidly weigh the grain as it is delivered from a separator, bin, elevator, corn-sheller, or any other source of supply and discharge it into a bin, wagon-box, or other receptacle provided for that purpose.

The invention may also be said to consist in the novel arrangement and combination of parts hereinafter described, and more particularly pointed out in the claims.

In the accompanying drawings, which illustrate the invention, Figure 1 represents a side elevation of my improved grain-meter secured upon the top of a separator. Fig. 2 is a plan view of the same. Fig. 3 is a vertical section of the hopper, taken on line III III of Fig. 2. Fig. 4 is a vertical sectional view of the segmental housing, taken on line IV IV of Fig. 1.

In the drawings, 1 indicates the upper portion of a separator, provided with the usual or any preferred grain-elevator 2, having a discharge-spout 3 at its upper end.

4 indicates the improved hopper, which is located vertically below spout 3 and is divided into four compartments 5 by radial partitions 6, which are secured at their opposite sides to disks 7, forming the sides of the hopper and provided at their outer sides with rings 7^a, having flat sides which fit against the disks and rounded outer sides which add to their rigidity and prevent them and the disks from bending under the strain to which they are subjected, said rings having four equally-spaced outwardly-extending stop-pins 7^b.

Hopper 4 is mounted upon a centrally-located transverse shaft 8, journaled at its opposite ends in bearings 9, formed integral with the outer ends of brackets 10, secured to a transverse plate 11, which is removably fastened to the down-spout of the elevator by clamps and bolts 12 13, respectively. The

front portion of the hopper is inclosed by a snugly-fitting segmental housing 14, provided at its opposite sides with marginal flanges 15 and at its lower portion with a spout 16, carrying a collar 17, having two oppositely-disposed arms 18, provided with pins 19, adapted to receive a swivel-spout 20, through which grain from the meter may be discharged into a wagon-box or other receptacle. The hopper is normally held in the position shown in Fig. 1 by a weigh-beam 21, fulcrumed near its rear bifurcated end 22 upon a knife-edge bearing 23 and provided at its forward graduated portion with a poise 24, adapted to be secured at any point thereon by a set-screw 25. The upward movement of the bifurcated end 22 is limited by contacting with pins 26, projecting from the opposite sides of the segmental housing, beyond which said ends project into the path of pins 7^b, so the latter will contact therewith and hold the hopper in the above-described position until its upper forward compartment receives sufficient grain to overbalance poise 24, when the bifurcated end 22 of the weigh-beam will be forced out of the path of the contacting pins 7^b as the hopper is rotated by its charge of grain. As the contacting pins 7^b pass free of the bifurcated end 22 the latter is instantly reelevated in contact with pins 26 by poise 24 in order to be in position to intercept the succeeding stoppin 7^b, and thus prevent the hopper from completing more than one-fourth of a revolution, which is ample movement for the discharge of its load into spout 16, and to stop it in position to receive another charge from spout 3. This operation is repeated until the elevator is stopped. The opposite ends of knife-edge bearing 23 are secured in jaws 27, formed at the upper end of a bracket 28, secured upon the top of the separator and provided with a support 29 for holding the segmental housing in position.

From the above description it is apparent that I have produced a grain-meter which is simple in construction and thoroughly effective for the purpose intended.

Having thus described my invention, what I claim, and desire to secure by Letters Patent, is—

1. In a grain-meter, a hopper comprising two disks forming the sides thereof, radial par-

titions secured at their opposite sides to the disks, a transverse shaft extending through the central portion of the hopper and suitably journaled at its outer ends, rings secured to the outer sides of the hopper, stop-pins projecting, therefrom, and a fulerum weigh-beam having one of its ends arranged in the path of the stop-pins and provided at its opposite end with a poise, substantially as described.

2. A hopper divided into a plurality of compartments for receiving successive charges of grain, a central transverse shaft upon which said hopper is mounted, a pair of triangular brackets arranged at the opposite sides of the hopper, bearings formed integral with the outer ends of the brackets to receive the opposite ends of the transverse shaft, a plate to which the opposite ends of the brackets are secured, clamps for securing the plate to one of the spouts of the elevator, and means for weighing the grain in the hopper, substantially as shown and described.

3. In a grain-meter, the combination of an elevator having a discharge-spout, with a journaled hopper adapted to receive the grain discharged from said spout, a housing inclosing the front end of the hopper and arranged eccentrically therewith and extending downwardly from a point adjacent to the lower terminal of the spout to a suitable distance below the hopper, marginal flanges forming the sides of said housing and which are

centric with and overlap the sides of the hopper, and a spout secured to the lower end of the housing, substantially as shown and described.

4. In a grain-meter, a journaled hopper, a housing inclosing the front end of said hopper, a spout secured to the lower end of the housing, a collar embracing the spout, a pair of oppositely-disposed arms secured to the collar, pins secured to the said arms, and a spout which is swiveled to said pins, substantially as described.

5. In a grain-meter, a journaled hopper divided into a plurality of compartments, rings secured to the opposite sides of said hopper, stop-pins projecting from the rings and which are equal in number to the compartments of the hopper, a housing inclosing the front end of the hopper, a pair of pins projecting from the opposite sides of the housing, a weigh-beam having a bifurcated end adapted to engage the pins on the housing and rings, a bracket provided with upwardly-disposed jaws between which the weigh-beam is pivoted, and a support projecting from the rear end of the bracket for the purpose of holding the housing.

In testimony whereof I affix my signature in the presence of two witnesses.

JOHN S. BLAKELY.
